UNITED STATES PATENT OFFICE.

JAMES C. GARNER, OF DALLAS, TEXAS, ASSIGNOR, BY MESNE ASSIGNMENTS, TO GARNER REGIN MACHINERY COMPANY, OF HOUSTON, TEXAS, A CORPORATION OF TEXAS.

COTTON-CLEANER.

1,180,132.

Specification of Letters Patent. Patented Apr. 18, 1916.

Application filed December 6, 1909. Serial No. 531,647.

To all whom it may concern:

Be it known that I, JAMES C. GARNER, a citizen of the United States, residing at Dallas, in the county of Dallas and State of Texas, have invented a new and useful Cotton-Cleaner, of which the following is a specification.

This invention has relation to cotton cleaners and it consists in the novel construction and arrangement of its parts as hereinafter shown and described.

The object of the invention is to provide a simple and an effective apparatus for cleaning lint or ginned cotton and is generally known as a reginner.

With the above objects in view, the cleaner includes a stand upon which is journaled for rotation a series of saws disposed in planes at acute angles to their axis of rotation, and means for shifting the series of saws laterally as the said series rotates upon its axis. The series of saws is arranged to rotate over in a downward direction toward the cotton as it is introduced to the saws and a rotating brush is arranged to co-operate with the saws to remove the cotton from the same and the said brush is adapted to turn upon its axis over and away from the saws. A beater is journaled for rotation in the machine and is located so that it may operate upon the cotton while it is held by the teeth of the saws. After the refuse has been removed from the cotton and the cotton has been removed from the saws, pneumatic means are provided for conveying both the refuse and the reginned cotton away from the cleaner.

A further object of the invention is to provide in a machine of the character stated, means of special arrangement for feeding the material to the saws and for stuffing the material in the receptacle inclosing the feeding mechanism.

In the accompanying drawings Figure 1 is a longitudinal sectional view of the cotton cleaner. Fig. 2 is a top plan view of the same with parts broken away. Fig. 3 is a side elevation of the machine viewing the same at one side. Fig. 4 is a side elevation 50 of the machine at the opposite side. Fig. 5 is an end elevation with parts broken away of a device used upon the machine for transmitting movement to the stuffing rolls

thereof. Fig. 6 is a sectional view of said device. Figs. 7 and 8 are detailed views of a band guide upon the machine.

The cotton cleaner includes a stand or frame 1, upon which is journaled for rotation a saw shaft 2. A series of saws 3 are arranged upon the shaft 2 and the said saws lie in planes at acute angles to the axis of the shaft 2. The shaft 2 is arranged to slide longitudinally in its bearings and is provided at one end portion with a collar 4, having a peripheral groove 5. A pintle 6 is mounted upon one side of the frame 1 and a pulley 7 is journaled for rotation upon the said pintle. The said pulley 7 is provided at one side with an extended hub 8 upon which is located an annular flange 9 which is continuous and pitched at an angle to the axis of the hub of the said pulley. The said flange 9 lies in the groove 5 provided in the collar 4.

Any suitable means may be provided for rotating the pulley 7 and the means herein shown consists of a belt 10 which passes around the said pulley and around a similar pulley 11 mounted upon a stub-shaft 12. The said stub-shaft 12 forms a portion of a belt tightening device as will be hereinafter explained. A belt pulley 13 is fixed to the end portion of the saw shaft 2 and a pulley 14 is mounted on the stub-shaft 12. The shaft 12 is journaled in bearings mounted upon the slidable frame 15 which in turn is provided with a threaded bolt 16 upon which is mounted a hand wheel 17. A cross bar 18 is provided with a threaded perforation which engages the thread of the said bolt, the hub of the said wheel bearing at one end against said cross bar 18 of the frame of the machine. Thus means are provided for shifting the frame 15 and its attachments and the said frame and its attached part constitute a belt tightener as above referred to.

A shaft 20 is journaled in the frame 1 behind the saw shaft 2 and a brush of cylindrical form, said brush being designated by the numeral 21 is mounted upon the shaft 20. A belt pulley 22 is mounted upon the end portion of the shaft 20. A belt 23 passes around the forward portion of the pulley 13 then under and against the rear portion of the pulley 14 then over the front

portion of the pulley 22. The upper run of the belt 23 moves in a downward direction and consequently the shaft 2 is rotated in the opposite direction from the shaft 20. Thus it will be seen that the series of saws carried by the shaft 2 rotate over in a downward direction while the brush 21 carried by the shaft 20 turns over away from the saws. At the same time rotary movement is transmitted from the stub-shaft 12 through the pulley 11 and belt 10 to the pulley 7 and as the flange 9 is carried around by the hub extension 8 of the said pulley the collar 4 is reciprocated laterally which in turn reciprocates the saw shaft 2 longitudinally. The shaft 20 is journaled in the bearings 24 which in turn are adjustably mounted upon the frame 1 as in Figs. 3 and 4 of the drawings, and the shaft 2 is journaled in the bearings 25 which are also adjustably mounted upon the frame 1 as shown in Fig. 4. By this arrangement it will be seen that the saws may be positioned remote from or in close proximity to the periphery of the brush 21 as desired. Bearings 26 are slidably mounted in guides located at the sides of the frame 1, and screw devices 28 are connected with the said bearings for the purpose of adjusting the same and holding them in adjusted position. A shaft 29 is journaled in the bearings 26 and is provided upon its intermediate portion with a mote brush 30 which is located under and preferably somewhat to the rear of the gang 35 of saws 3. A belt pulley 31 is fixed to one end of the shaft 29 and a belt pulley 32 is fixed to the shaft 2. A belt 33 passes around the pulleys 31 and 32 and is adapted to transmit rotary movement from the shaft 40 2 to the shaft 29. A belt tightening device 34 is attached to the side of the frame 1 and is provided with a roller 35 which bears against one of the runs of the belt 33. By this arrangement it will be seen that the brush 30 rotates in the same direction as the gang of saws 3 but inasmuch as the upper portion of the brush is adjacent the lower portion of the gang of saws the brush as it rotates may operate upon material carried by the teeth of the saws in a manner hereinafter to be pointed out. The said brush 30 constitutes the beater herein before referred to.

A stub-shaft 36 is journaled for rotation 55 between one side of the frame 1 and a bracket 37 located at the same side of the said frame. A belt pulley 38 is fixed to the shaft 36 and a pulley 39 is fixed to the shaft 2. A belt 40 passes around the pulleys 39 and 38 and is adapted to transmit rotary movement from the shaft 2 to the stub-shaft 36. A trough 41 is located between the sides of the frame 1 at a point below the brush 30. A worm auger 42 is journaled for rotation in the said trough 41 and its shaft

is provided at a projecting end with a belt pulley 43. A belt pulley 44 is fixed to the shaft 36, and a belt 45 passes around the pulleys 43 and 44.

The bracket 37 is provided with a long bearing 46 in which a shaft 47 is journaled for rotation. A beveled pinion 48 is fixed to the lower end of the shaft 47 and meshes with a beveled pinion 49 fixed to the stub-shaft 36. The shaft 47 is provided in the vicinity of its upper end with a worm 50 which meshes with worm wheels 51 and 52 mounted upon the shafts 53 and 54 respectively. The said shafts 53 and 54 are journaled in the frame 1 and are provided upon their intermediate portions with rollers 55 and 56 respectively. A shaft 57 is journaled for rotation in the frame 1 at a higher elevation than the shaft 54 and between the said shaft 54 and the saw shaft 2. A roller 58 is mounted upon the shaft 57 and an endless belt 59 passes around the rollers 56 and 58. By reason of the fact that the shaft 57 is positioned at a higher point than the shaft 55 the upper run of the belt 59 is in an inclined position, its inclination being in an upward direction at that portion which is nearest the gang of saws. A gear wheel 60 is fixed to the shaft 57 and meshes with a pinion 61 which is journaled upon a pin 62 located at the side of the frame 1. A lower feeder shaft 63 is journaled in the frame 1 between the delivery end of the belt 59 and the gang of saws, and a roll 64 is carried by the shaft 63. A pinion 65 is fixed to the end of the shaft 63 and meshes with the pinion 61. If desired the pinions 60, 61 and 65 may be duplicated and a set used at each side of the frame 1. By this arrangement it will be observed that means are provided for transmitting orbital movement to the belt 59 and from the shaft 57 rotary movement is transmitted to the feed roll 64.

Plates 65' are slidably mounted in guides 66 located upon the sides of the frame 1 and are held in the depressed position under tension of springs 67 which bear at their lower ends upon the upper edges of the said plates. The upper ends of the springs 67 bear against the lower sides of nuts 68 which are screw threaded upon rods 69 also attached to the frame 1. By this provision means are afforded whereby the tension of the said springs may be regulated.

A shaft 70 is journaled at its ends in the plates 65' and is provided upon its intermediate portion with a roller 71. An endless belt 72 passes around the rollers 55 and 71, and by reason of the fact that the shaft 70 is located at a lower point than the shaft 53 the lower run of the said belt 72 is inclined in a downward direction toward the saws 3. The belt 72 is not so long as the belt 59 but their inner ends terminate at approximately

the same vertical plane consequently the outer end of the belt 59 projects beyond the outer end of the belt 72. A gear wheel 73 is fixed to the shaft 70 and meshes with a gear wheel 74 journaled upon a pin 75 fixed to the side of the frame 1. The pinion 74 meshes with a pinion 76 fixed to the end of a shaft 77 also journaled in the plates 65'. If desired the gear wheels and pinions 73, 10 74 and 76 may be duplicated and a set located at the opposite sides of the frame 1. A feeder roll 78 is mounted upon the intermediate portion of the shaft 77 and is located immediately above the feeder roll 64. 15 Thus it will be seen that as rotary movement is transmitted from the shaft 47 to the shaft 53, the belt 72 is moved in an orbit about the rollers 55 and 71, and at the same time the feeder roll 78 is rotated in a direction so 20 that its side nearest the delivery end of the belt 72 moves toward the roll 64.

An arbor 79 is journaled for rotation upon the upper portion of the frame 1 and a sprocket wheel 80 is fixed to the end of the 25 said arbor. A sprocket wheel 81 is fixed to the shaft 53 and a sprocket chain 82 passes around the sprocket wheels 80 and 81 and is adapted to transmit rotary movement from the shaft 53 to the said arbor 79. A cone 83 is fixed to the arbor 79 and a shaft 84 is journaled in the frame 1 below the said arbor 79. A stuffing roll 85 is mounted upon the intermediate portion of the shaft 84 and a cone 86 is fixed to the 30 outer portion of the said shaft 84 and lies adjacent the cone 83. The axes of the cones 83 and 86 are parallel but the apices of the said cones are disposed in opposite directions. An arm 87 is fixed to the side of the 35 frame 1 adjacent the cones 83 and 86 and a guide 88 is adjustably mounted upon the said arm and is adapted to be secured in an adjusted position thereon by means of a set screw 89 which passes transversely through the said guide and is adapted to impinge 40 against the said arm. An endless band 90 preferably of flexible material such for instance as leather or rubber is held in an opening provided in the guide 88 and lies 45 between the adjacent portions of the cones 83 and 86 and is in contact with both of the said cones. Thus it will be seen that while means are provided for transmitting rotary movement from the shaft 53 to the 50 arbor 79 at a constant rate of speed means are provided for varying the rate of speed at which the shaft 84 rotates with the relation to the arbor 79. If it is desired that the shaft 84 shall rotate at a fast rate of 55 speed with relation to the said arbor the guide 88 is shifted so that the band 90 is carried toward the smaller end of the cone 86 and the larger end of the cone 83. Should it be desired that the shaft 84 shall rotate at a 60 slow rate of speed with relation to the ar-

bor 79 the guide 88 is moved so that the band 90 is positioned between the larger end portion of the cone 86 and the smaller end of the cone 83.

Plates 91 are slidably mounted in guides 92 provided upon the sides of the frame 1 and a shaft 93 is journaled for rotation in the said plate 91. A stuffing roll 94 is mounted upon the intermediate portion of the shaft 93. Springs 95 bear at one end 75 against the plates 91 and at their other ends against lugs 96 formed upon the frame 1 and are under tension with a tendency to hold the stuffing roll 94 toward the stuffing roll 85. The stuffing rolls 85 and 94 are located above the projecting end portion of the lower conveyer belt 59.

A wind trunk 95' is located below the gang of saws 3 and the rear end of the said trunk communicates with a duct or pipe 96'. 85 An air blast pipe 97 is mounted upon the frame 1 in front of the forward end of the trunk 95' and is provided with a discharge outlet 98. The outlet communicates with the forward end of the trunk 95' below the 90 saws 3.

A trunk 99 receives at its forward end the upper portion of the rotary brush 21 and at its rear end communicates with a duct or pipe 100. In the lower portion of 95 the trunk 95' and approximately in alignment with the outlet of the discharge passage 98 of the pipe 97 the trough 41 is located in which the worm auger 42 is journaled for rotation.

During the process of cleaning cotton the apparatus operates upon the same as follows:—Assuming power to be applied to the machine so as to drive the various parts in the manner hereinbefore set forth, the cotton, which is placed in the inlet of the machine, is engaged by the stuffing rollers 85 and 94 and by them fed downward upon the front end of the belt 59 which projects beyond the belt 72. The fiber is carried rearward by this belt and by the coöperation of the converging upper run of the lower belt and the lower run of the upper belt the fiber is compacted and formed into a more or less homogeneous ribbon or bat. The bat or 11 fiber thus formed is delivered from the belts 59 and 72 to the feed rollers 64 and 78 which present the end of the bat to the toothed surfaces of the saw cylinder. The teeth of the rapidly turning saw cylinder separate the fiber in minute particles from the bat and sweep it downward and rearward. During this movement of the particles of fiber which adhere to the teeth, particles of dirt and impurities are freed and allowed to 12 fall into the trunk 95', the heavier impurities finding their way into the trough 41 while the lighter particles of dirt are blown by the air jet from the nozzle 98 into the 13 conduit 96'. The matter blown into the

thereby particles of dirt and impurities are free to fall away from the fiber, substantially as set forth.

7. In a cotton reginning machine, conning, traveling feeding members in combination with a pair of feeding cylinders and a single toothed cylinder to which the air of feeding cylinders are adapted to feed cotton radially and means for producing relative reciprocal movement between said single cylinder and said pair of feeding cylinders.

8. In a cotton cleaner having a feeding hopper with two sides formed of traveling

aprons, a pair of feeding cylinders and a 15 toothed cylinder, said feeding cylinders being mounted to feed the cotton radially to said toothed cylinder and means for longitudinally reciprocating one of said cylinders.

In testimony that I claim the foregoing as my own, I have hereto affixed my signature in the presence of two witnesses.

JAMES C. GARNER.
